UNITED STATES PATENT OFFICE.

EDWARD D. PRIEST, OF SCHENECTADY, NEW YORK, ASSIGNOR TO GENERAL ELECTRIC COMPANY, A CORPORATION OF NEW YORK.

COOLING DYNAMO-ELECTRIC MACHINES.

SPECIFICATION forming part of Letters Patent No. 727,685, dated May 12, 1903.

Application filed November 2, 1900. Serial No. 35,239. (No model.)

To all whom it may concern:

Be it known that I, EDWARD D. PRIEST, a citizen of the United States, residing at Schenectady, county of Schenectady, State of New York, have invented certain new and useful Improvements in Cooling Dynamo-Electric Machines, of which the following is a specification.

My invention relates to means for cooling dynamo-electric machines, and especially railway-motors, in order to prevent overheating of the armature or rotary member and the other parts of the motor.

It consists in devices for causing air to enter at one end of the motor, preferably the pinion end, and to pass through it to the other end through longitudinal ducts formed in the core and radial air-passages formed in the core and the spiders on which it is supported.

This effect is produced by an air-shield which closely embraces the pinion end of the armature, constituting an annular chamber communicating with the ducts and air-passages in the core and spiders. Pipes or flues run from this chamber to the outside of the motor frame or casing and admit cool air to the chamber only. At the commutator end of the motor the frame is provided with one or more openings to permit the heated air to escape. The current of air through the shield and passages is produced by the centrifugal movement of the air induced in said passages by the rapidly-rotating armature.

The drawing is a longitudinal half-sectional elevation of the railway-motor embodying my improvements.

The head A at the pinion end of the motor extends inwardly to form a bearing for the armature-shaft and has an interior cylindrical shoulder *a*, on which is fitted a ring or cylinder B, extending inwardly and closely embracing the head of the spider C. At one or more points in the peripheral surface of the cylinder or ring there is an opening *b*, communicating with one of the pipes or flues D, which run out radially through the frame or casing E of the motor, between the field-magnets and the end of said frame.

It will be seen that the head A, the ring B, and the spider C constitute an annular chamber concentric with the shaft and commun-

cating with the outside air only by means of the pipes D. The ring B, together with the walls of the flue or flues D, constitutes a fixed shield which closely embraces the armature, 55 so that practically no heated air can flow again into the armature-openings; but at the same time the construction is such that there is nothing to prevent the usual free end play or thrust of the armature.

The armature-core F is preferably laminated, as shown, and is divided into sections by spacing-rings G, leaving narrow radial passages H, through which air can pass out between the coils L from the ducts I, of which 65 there are several running lengthwise through the core. Passages H' are formed in the spiders C C', extending outwardly from the ducts I. At the commutator end of the motor one or more passages e are made in the 70 frame to permit the heated air to escape.

The operation of my device is as follows: When the armature is in rapid rotation, it acts like a centrifugal blower to expel the air from the passages H H'. Inasmuch as no air 75 can enter the passages except through the pipes D, the annular chamber above referred to, and the ducts I, it follows that a current of cool air will flow in through the said pipes and chamber and out through the ducts I and 80 passages H H', entering the space M, surrounding the armature, inside the frame E, and thence escaping through the hole e and rapidly carrying off the heat generated in the armature. A practical test of the invention 85 shows that the rise in temperature of the coils, core, spools, and frame is less by from 10.5° to 18° centigrade than it would be without this device, the greatest reduction being in the coils and core, where the heating 90 effect is most injurious. The ring B fits so closely to the end of the spider that practically no air can enter it from the space M, so that the air can pass through the core but once, and thus a continuous supply of cool air 95 is insured.

What I claim as new, and desire to secure by Letters Patent of the United States, is—

1. The combination with an inclosed electric motor having a rotating element provided 100 with air-passages, whereby it operates as a centrifugal blower, said rotating element be-

ing journaled in the end of the motor-inclosure, of an inlet-opening in the side of the inclosure, and communications between said inlet and said air-passages alone.

5. 2. In an electric machine, the combination with a rotating element provided with cooling-passages, whereby said element operates as a centrifugal blower, of closed flues for connecting said passages with the outside of the machine.

3. In an electric machine, the combination with a rotating element provided with cooling-passages, whereby it operates as a centrifugal blower, of an annular chamber communicating with said passages, and closed flues connecting said chamber with the outside of the machine.

4. In an electric machine, the combination with a rotating element provided with cooling-passages, whereby it operates as a centrifugal blower, of a closed annular chamber communicating only with said passages and with the outside of the machine.

5. The combination, with a motor-frame, of an armature having longitudinal ducts and radial air-passages through its core, a ring tightly inclosing the end of the armature, and forming with an extension of the armature a chamber communicating with said longitudinal ducts, and pipes connecting the ring with the outside air.

6. The combination, with a motor-frame having an opening at one end and at the other end a head provided with an interior cylindrical shoulder, of a ring fitting said shoulder, and pipes running from said ring to the outside of the frame.

7. The combination, with an armature having the spiders C, C' containing air-passages H', the core F having air-ducts I and passages H, the ring B closely inclosing the spider C, and the pipes D extending from said ring.

8. In an electric machine, the combination with a rotating element formed with cooling-passages, whereby it operates as a centrifugal blower, of a ring or cylinder forming with the rotating element an annular chamber communicating with said passages, and closed flues connecting said chamber with the outside of the machine.

9. The combination with an electric machine provided with a casing and having cooling-passages in its rotating element, whereby the latter operates as a centrifugal blower, of a head closing the end of the casing and extending inside the latter to serve as a bearing for the rotating element, said cooling-passages having communication between the end of the machine and the end of the casing with the outside of the latter.

10. The combination with an electric machine provided with a casing and having cooling-passages in its rotating element, whereby the latter operates as a centrifugal blower, of a head closing the end of the casing and extending inside the latter to serve as a bearing for the rotating element, and passages con-

necting the outside of the casing with the interior of the machine only through the passages in the rotating element.

11. The combination with an inclosed electric machine having a rotating element formed with cooling-passages, whereby said element operates as a centrifugal blower, of a head forming a part of the inclosure and extending inside the inclosure to form a bearing for the rotating element, and closed flues connecting the said cooling-passages with the outside of the inclosure.

12. The combination with an inclosed electric machine having its rotating element provided with suitable cooling-openings, whereby said element operates as a centrifugal blower, of a head completing the inclosure and extending inside the latter to serve as a bearing for the rotating element, an annular chamber communicating with said openings, said chamber having communication also between the machine and the head with the outside of the inclosure.

13. The combination with an inclosed electric machine having a rotating element formed with cooling-passages, whereby said element operates as a centrifugal blower, of a head forming a part of the inclosure and extending inside the latter to form a bearing for the rotating element, and a ring forming with the head and rotating element an annular chamber which communicates with said cooling-passages and with the outside of the inclosure.

14. The combination with an inclosed electric machine having a rotating element formed with cooling-passages, whereby the said element operates as a centrifugal blower, of a head completing the inclosure at one end of said element and extending inside the inclosure to form a bearing for said element, the inclosure being provided with a suitable inlet through which air is drawn between the end of the machine and the end of the inclosure, and thence into the cooling-passages in the rotating element.

15. The combination with an inclosed electric machine having a rotating element formed with cooling-passages, whereby said element operates as a centrifugal blower, of a head inclosing the machine at the end and extending inside the inclosure to form a bearing for the rotating element, and openings in the sides of the machine-inclosure through which air is drawn into the space between the machine and the head, and thence into said cooling-passages, by the rotation of said element.

16. The combination with an inclosed electric machine having a rotating element provided with cooling-passages, whereby said element operates as a centrifugal blower, of a head inclosing the machine at the end and extending inside the inclosure to form a bearing for said element, and passages connecting the outside of the machine with the inside only through said cooling-passages in the rotating element.

17. The combination with an inclosed electric machine having a rotating element provided with cooling-passages, whereby said element operates as a centrifugal blower, of a head inclosing the machine at the end of said element and extending inside the inclosure to form a bearing for the latter, and an annular passage which connects the outside of the machine with said cooling-passages, said 5 annular passage being formed by portions of the rotating element and the head.
18. In an electric machine, the combination with a rotary element formed with ventilating-openings, of a shield closely embracing 10 said element to prevent reentrance of heated air into said ventilating-openings, and to per-

mit the usual end thrust of the rotary element.

19. In an electric machine, an inclosing casing, a rotating element, said rotating element 20 being provided with ventilating-openings, and a member also mounted in said casing closely embracing said element for preventing the entrance of air from said casing into said ventilating-openings and to permit the 25 usual endwise movement of said element.

In witness whereof I have hereunto set my hand this 31st day of October, 1900.

EDWARD D. PRIEST.
